WATER HEATING AND STEAM GENERATING UNIT

Filed April 21, 1944

UNITED STATES PATENT OFFICE

2,401,848

WATER HEATING AND STEAM GENERATING
UNIT

Philip B. Wallace, San Francisco, Calif.

Application April 21, 1944, Serial No. 532,041

6 Claims. (Cl. 122—181)

1

My present invention relates to a heat exchanger device having heat induced convection circulation, and more particularly relates to a boiler of simple and practical construction for heating water and/or generating steam.

An object of the invention is to provide a simple and inexpensive water heater or steam generating unit of novel construction which will be particularly applicable to non-industrial uses, such as the heating of water for homes, apartments, hotels and the like, or for generating low pressure steam.

Another object of the invention is to provide a novel boiler which can be constructed almost entirely of cylindrical members of different 15 lengths and diameters and in which the heat is applied in a novel and economical manner.

Another object of the invention is to provide an improved heat exchange and baffle arrangement for water heaters and the like in which the water being heated will be subjected to a reheating circulation by convection.

Another object of the invention is to provide a sectionalized water heating and steam generating unit which may be easily and conveniently disassembled for a periodic removal of scale and other foreign particles to the end that a maximum efficiency will be maintained within the unit at all times.

In the construction of hot water heaters and steam generators of the size and type contemplated by my invention, it has in the past been the custom to construct the various parts of cast iron which may take many complicated shapes and which, because of this fact, is expensive and difficult to clean and maintain. It is, therefore, a further object of my invention to provide a device which can be constructed entirely of wrought metal pipe in a practical and inexpensive manner and which may be periodically disassembled for the removal of scale in a simple and expeditious manner.

Other objects and advantages of the invention will be in part evident to those skilled in the art, and in part pointed out hereinafter in the following description taken in connection with the accompanying drawing, wherein there is shown by way of illustration and not of limitation a preferred embodiment of the invention.

In the drawing;

Figure 1 is a sectional view taken along the longitudinal center line of a multi-stage water heating and steam generating unit constructed in accordance with a preferred embodiment of the invention,

2

Figure 2 is a fragmentary sectionalized view showing a modification of the device as illustrated in Figure 1 of the drawing, and

Figure 3 illustrates a further modified and simpler form of the invention for use with a heat conducting flue.

In Figure 1 of the drawing I have shown a multiple stage water heating and/or steam generating unit constructed in accordance with my invention and employing a multiplicity of nested and concentrically arranged lengths of pipe that are assembled and associated with a single hot gas conducting flue in a novel manner. In this arrangement the hot gases used for heating may be taken from any suitable source, or I may employ a gas or oil burner 10 to provide the hot gases which, as here shown, pass upwardly through a flue 11 formed by a length of pipe that has an outwardly extending flange 13 at a point slightly below its upper end, and a second outwardly extending flange 14 near its lower end. Secured to the underside of the flange 13 and spaced from the flue 11 there is a downwardly extending length of pipe 15 which carries an inwardly extending flange 16 that is secured to the underside of the flange 14 by means of bolts 17. The outer length of pipe 15 also has a fluid introducing inlet conduit 18 through which a fluid may be introduced into the annular chamber thus formed around the flue 11 and between the said flue and the pipe 15. Positioned within this annular chamber midway between the flue 11 and the pipe 15, and with its upper end spaced from the flange 13 there is also an additional length of pipe 19 that has a plurality of notches or circulation permitting apertures 20 in its lower end through which a fluid may pass from one to the other side thereof. This baffle forming length of pipe 19 is held concentrically between the flue 11 and the pipe 15 by means of spaced bosses 21 and 22 that project from the flue 11. At this point it should be noted that the gas or oil burner 10 is positioned within the flue 11 at a point where the flame therefrom will be applied to the inside of the flue wall at a point above the notched apertures 20 formed in the bottom of the baffle forming pipe 19 and, as a result, the fluid in the chamber surrounding the flue 11 will be caused to circulate in a vertical direction around the baffle forming pipe 19.

The assembly thus far described may be considered to form the first stage of the heater or steam generator shown in Figure 1 of the drawing. As for the second stage of this embodiment 55 of the invention, it will be noted that the out-

wardly extending flange 13 carried by the flue 11 serves as a support for a vented hood 23 having vents 24 which permit the hot gases to escape from the flue 11 directly to the atmosphere. If desired, it is contemplated that the hood 23 may be provided with an extension or pipe that will conduct the hot gases to a chimney for discharge out of a room or confined space in which the heater may be installed. This hood 23 fits over an upwardly extending end of the flue 11 and it has a central aperture through which a length of pipe 26 extends. This pipe 26 is supported by an annular collar 27 that is welded thereupon which rests upon the hood 23, and at its lower end it is closed, as at 28, so that it will form an elongated passageway through which the water or steam may flow in passing to the discharge outlet. This pipe 26 also in turn supports an internally disposed length of pipe 29 that extends downwardly to a point closely adjacent the bottom or closed end 28 of the pipe 26. The internally disposed length of pipe 29 has a supporting flange 30 that is secured by bolts or other means to a flange 31 at the upper end of the pipe 26. The pipe 26 is also here shown as provided with a discharge outlet 32 through which the hot water or steam may be withdrawn from the unit. A cap 33 is provided for closing the upper end of the pipe 29, and immediately below this cap 33 there is an inlet conduit 34 that is connected through a pipe 35 to the interior of the annular chamber formed between the flue 11 and the pipe 15 which, as will now appear, forms the outer wall or casing of the unit. The internally disposed length of pipe 29 is here shown as having a series of spaced bosses 36 which serve to maintain it in central relation with respect to the walls of the pipe 26, and at a point approaching the upper end of the flue 11, this pipe 26 may also, if desired, be provided with a plurality of spaced apertures 37 that lie in a horizontal plane and provide for a restricted recirculation of the water by convection as the water or steam is being heated. In order to improve the convection characteristics provided for by the apertures 37, it is contemplated that the lower or closed end 28 of the pipe 26 will be covered externally with a heat insulating means 38 that will prevent to some extent, the direct application of heat to the outer walls of the pipe 26 at a point where the relatively cooler water or steam is discharged from the lower end of the pipe 29.

With this arrangement it will be seen that when the flue 11 is heated, as described above, and water is admitted through the inlet conduit 18 and withdrawn from the outlet conduit 32, the heat within the flue 11 will be conducted through the wall of said flue to the water in the annular chamber formed between the flue 11 and the outer pipe 15 and, because of the baffle 19, this water will be caused to circulate by convection around the baffle in the manner indicated by the arrows applied to this figure of the drawing. At the same time, if water or steam is being withdrawn from the heater, the water will flow upwardly through the pipe 35 and the inlet conduit 34 to the interior of the internally disposed length of pipe 29 and be discharged at the lower end thereof and into the lower end of the pipe 26. As the water circulates through this pipe 26, the heat in the flue 11 will be conducted to a thin film of water between the pipes 26 and 29 and, because of the restricted apertures 37, there will be formed a second convection circulation of the water as it is being heated. This

latter convection circulation will be particularly active in the event that the water or steam is not being withdrawn from the generator at a rate corresponding to the heating thereof. In this operation the water in the outer annular chamber between the pipe 15 and the flue 11 will be preheated, and in the inner space between the pipes 26 and 29 it will be subjected to a final heating or steam generating operation.

From the above it will be seen that by the arrangement here described, I have provided a simple, practical and inexpensive device that is adapted to heat water and/or generate low pressure steam in an efficient and economical manner. In the operation of water heaters and steam generators it is well known that scale and other sediment is precipitated from the water during the heating operation and it is, therefore, also important, if full efficiency is to be maintained in a device of this character, to provide means whereby the device may be conveniently and effectively cleaned of this scale and other matter, and to this end it will be noted that the flue 11, with its outwardly extending flanges 13 and 14, is so constructed that it may be completely removed from the outer length of pipe 15 by an axial displacement thereof. At the same time, the baffle forming pipe 19 will also be exposed in such a manner that it, too, may be readily scraped and cleaned of any scale or other objectionable matter. The pipe 26, with its flange 21, is also arranged to be lifted free of the flue 11 with the vented hood 23 so that its exterior surface may be cleaned of soot or the like, and by releasing the flange 30 of the internally disposed length of pipe 29, it will be possible to withdraw this latter pipe so that it and the pipe 26 can be cleaned of scale and the like. In order to permit this latter operation, the pipe 35 is shown as having a union 39 for disconnecting the inlet conduit 34 from the pipe 35. As an auxiliary, the inlet conduit 34 may have a T-coupling 40 from which an additional conduit 41 extends, either for the purpose of introducing fresh water, or withdrawing preheated water directly from the annular chamber between the flue 11 and the outer pipe 15. Because of the difference in the temperature of the flue 11 and the outer pipe 15, it is possible that there may exist some differential in the rate of expansion and/or contraction of these members and, therefore, the outer pipe 15 is here shown as having a single outwardly extending corrugation 42 that is adapted to compensate for any difference in the expansion or contraction which may occur between the flue 11 and pipe 15. Instead of this corrugation 42, it will also be possible to compensate for any difference in expansion or contraction between these parts of the unit by providing a corrugated flue 11. In this latter event, the corrugations of such a flue would have additional advantage of providing an increased heat transferring surface with which the water in the outer annular chamber would contact.

Reference is now made to Figure 2 of the drawing which illustrates a modification of the invention that, in other respects, is substantially identical to the arrangement described above. In this arrangement the outer annular chamber between the flue 11 and the outer length of pipe 15 is here shown as sealed at its bottom by the provision of suitable packing rings 43 that are disposed between the flanges 14 and 16 carried respectively by these lengths of pipe. As here shown, the inner chamber is formed by a length

of pipe 44 that is closed at its end and extends downwardly below an oil or gas burner 45 which is positioned within the flue 11. Positioned within the length of pipe 44 there is a length of pipe 46 that in other respects is similar to the internally disposed length of pipe 29 previously described. In this arrangement it will be seen that since the lower end of pipe 44 is not exposed to heat, but is rather exposed to the inflowing fresh cool air, there will be no necessity for the heat insulating covering previously referred to as applied to the lower end of the inner pipe 26. Because of this construction, it will also be possible to provide the inner pipe 44 with a blow-off valve 47 that will provide for a periodic discharge of any sediment which may collect in the heater at this point. Like the above described arrangement, it will be understood that since the internally disposed length of pipe 46 terminates at a point below the burner 45, there will also be created a difference of temperatures in the water at this point which will tend to set up the desirable convection circulation, which is an important aspect of this invention.

In Figure 3 of the drawing there is shown a more simplified embodiment of the invention. This arrangement is particularly suited to the heating of water in industrial plants where there exists a large amount of excess heat that is generally collected in a large flue which is connected to a more distant stack. In this illustration I have shown only three similar units, designated by the numeral 48, that are arranged so as to extend vertically through a horizontally disposed flue 49. In this arrangement the units 48 are projected through aligned openings in the top and bottom walls of the flue 49 and they are supported in this position by means of collars 50 that rest upon a top wall 51 of the flue 49. At this point it will be noted that the lower ends of these units 48 are allowed to project downwardly beyond the limits of a lower wall 52 of the flue 49 where they will be exposed to the surrounding air which will be at a considerably lower temperature than the gases in the flue 49. As shown in section at the left of this figure of the drawing, each of these units 48 is provided with a downwardly extending internally arranged length of pipe 53 which terminates within that portion of the units 48 extending beyond the lower wall 52 of the flue 49. These internally arranged lengths of pipe 53 are also shown as provided with restricted apertures 54 which permit a convection circulation within the water contained in each of these units. At their upper ends these internally disposed pipes 53 are each shown as connected to a water inlet manifold 55, and at the sides of the units 48 and above the wall 51 of the flue 49 these units each have an outlet conduit 56 which connects with a hot water pipe or manifold 57. In this way when water is introduced to the units 48 through the pipes 53 from the inlet manifold 55, it will be subjected to heating by the hot gases within the flue 49 and can then be withdrawn through the outlet conduits 56 and the manifold 57 to a point of use. The units 48 are each also here shown as having a removable plug 58 which will permit a removal of any sludge or scale that may accumulate at the bottoms of the units 48.

While I have, for the sake of clearness and in order to disclose the invention so that the same can be readily understood, described and illustrated specific devices and arrangements, I desire to have it understood that the invention is not limited to the specific form disclosed, but may

be embodied in other ways that will suggest themselves to persons skilled in the art. It is believed that this invention is new and it is desired to claim it so that all such changes as come within the scope of the appended claims are to be considered as part of this invention.

Having thus described my invention, what I claim and desire to secure by Letters Patent is:

1. In a fluid heating unit of the character described, the combination of a vertically disposed cylindrical pipe having a closed bottom end, means for applying heat to the outside of said pipe at a point above its closed bottom end, and a fluid directing conduit forming a baffle extending longitudinally into said pipe and adapted to discharge a fluid to be heated into the interior of said pipe below the point of heat application, whereby said fluid will be subjected to a violent convection circulation in said pipe as it is heated.
2. In a fluid heating unit of the character described, the combination of a vertically disposed cylindrical pipe having a closed bottom, means for applying heat to the outer wall of said pipe at a point above its closed bottom, and a fluid directing cylindrical baffle extending longitudinally into said pipe and adapted to direct a fluid to be heated against the inner wall of said pipe below the point of heat application, whereby the fluid in said pipe will be caused to circulate by convection as it is heated.
3. In a hot water heater of the character described, the combination of a vertically extending flue, a closed relatively long cylindrical pipe suspended within said flue and having a fluid discharge outlet at its upper end, a fluid introducing conduit extending through the top and downwardly to a point closely adjacent the bottom of said pipe, heat insulating means surrounding the lower end of said pipe at the point where the fluid is discharged from said fluid introducing conduit, said fluid introducing conduit also having restricted apertures at its upper end communicating with the interior of said pipe, and means for supplying hot gases to said flue above said heat insulating means, whereby the fluid within said pipe will be caused to recirculate by convection as it is heated.
4. In a hot water heater of the character described, the combination with a hot gas conducting flue of, a closed substantially cylindrical pipe suspended within said flue and having a fluid discharge outlet at its upper end, a fluid introducing conduit extending within and throughout substantially the entire length of said pipe and adapted to discharge a fluid to be heated at the bottom thereof, said cylindrical pipe being insulated from the hot gases in said flue at the point where the fluid is discharged from said fluid introducing conduit, and said fluid introducing conduit having restricted recirculation apertures at its upper end communicating with the interior of said cylindrical pipe, whereby the fluid within said pipe will be subjected to a partial recirculation through said fluid introducing conduit as it is being heated.
5. In a water heating unit of the character described, the combination of a vertically disposed hot gas conducting flue, a length of pipe positioned concentrically about said flue and supported thereupon at its top and bottom by connecting flanges to form an outer annular chamber about said flue, a cylindrical baffle positioned within, and spaced from the top of and extending substantially the entire length of said annular chamber and having notches through

which a fluid within the chamber may circulate by convection, a second pipe closed at its lower end and extending downwardly into said hot gas conducting flue and projecting above the upper end of said first length of pipe, a fluid conducting conduit having a flange coupling for closing the upper end of said second length of pipe and extending thereto to a point adjacent the closed end thereof, a connecting conduit between the top of said outer annular chamber and the top of said fluid conducting conduit, a fluid inlet for introducing a fluid into said outer annular chamber, and a fluid outlet at the top of said second length of pipe, whereby water within the unit will be simultaneously subjected to a preheating and recirculation within said annular chamber and to a final recirculation and heating within

the outer annular chamber, and to a final heating within the outer annular chamber.

5. A fluid heating unit of the character described, the combination of a hot gas conducting flue, a vertically disposed cylindrical pipe extending into said flue and having its bottom end insulated from the hot gases in said flue, whereby the heat of said hot gases will be applied to the outer wall of said pipe at a point above its closed bottom end, and a fluid directing cylindrical conduit extending longitudinally through said pipe and adapted to introduce a fluid to be heated into the insulated bottom end of said vertically disposed pipe, whereby an improved convection circulation will be established within said pipe as said fluid is heated.

said second length of pipe by the hot gases passing through said flue.

6. In a fluid heating unit of the character described, the combination of a hot gas conducting flue, a vertically disposed cylindrical pipe extending into said flue and having its bottom end insulated from the hot gases in said flue, whereby the heat of said hot gases will be applied to the outer wall of said pipe at a point above its closed bottom end, and a fluid directing cylindrical conduit extending longitudinally through said pipe and adapted to introduce a fluid to be heated into the insulated bottom end of said vertically disposed pipe, whereby an improved convection circulation will be established within said pipe as said fluid is heated.

PHILIP B. WALLACE.
